UNITED STATES PATENT OFFICE.

EDWARD W. POWERS, OF WALTHAM, MASSACHUSETTS.

AUTOMATIC CLOTHES-LINE REEL.

1,107,445.

Specification of Letters Patent. Patented Aug. 18, 1914.

Application filed June 19, 1911. Serial No. 633,949.

To all whom it may concern:

Be it known that I, EDWARD W. POWERS, a citizen of the United States, residing at Waltham, in the county of Middlesex and 5 State of Massachusetts, have invented new and useful Improvements in Automatic Clothes-Line Reels, of which the following is a specification.

This invention relates to a reel particularly adapted to be used in connection with clothes lines, the object of the invention being to provide a reel which may be readily attached to a stationary support and in which a clothes line may be contained, the 10 same being so arranged that the clothes line can be withdrawn to any desired extent from the reel and then locked in position.

The object of the invention is further to provide a reel in which the clothes line, 15 when not in use, may be quickly and automatically wound up within a suitable casing, which casing is so constructed as to protect the clothes line from the weather.

The invention consists in the combination 20 and arrangement of parts set forth in the following specification and particularly pointed out in the claim thereof.

Referring to the drawings: Figure 1 is a side elevation, partly in section, of my improved clothes line reel, the weight being shown broken away to save space in the drawings. Fig. 2 is a sectional elevation taken on line 2—2 of Fig. 1, the weight being omitted to save space in the drawings. 30 Fig. 3 is a sectional plan taken on line 3—3 of Fig. 1. Fig. 4 is a sectional plan similar to Fig. 3, illustrating a modification of the guide-roll and its support. Fig. 5 is a sectional elevation of the modified form of 35 guide-roll support illustrated in Fig. 4.

Like numerals refer to like parts throughout the several views of the drawings.

In the drawings, 6 is the casing which, with the exception of the rear wall 10, hereinafter described is formed of a single casting and is provided with ears 7, 7 through which extend screws 8, 8 by means of which the casing is attached to a suitable stationary support 9, such as the side wall of a 50 house.

The casing consists of a rear wall 10, two side walls 11, 12 and a top 13, the top constituting a cover and being concavo-convex in cross section for the purposes hereinafter 55 set forth. A stationary shaft 14 extends transversely of the casing and rotatably

mounted upon this shaft are two reels 15 and 16. The reel 15 is contained within a chamber 17 in the side wall 12 and has fastened thereto a cord 18, said cord having 60 fastened to one end thereof a weight 19 which operates to rotate the reel 15.

The reel 16 has fastened thereto one end of the clothes line 20, said clothes line extending from the reel 16 around a guide-roll 21, thence through a guide-eye 22 and from the guide-eye 22 the clothes line extends around different stationary hooks in the usual manner and is fastened to one of said hooks at its outer or free end, while that portion of the line adjacent to the reel is fastened by passing the same, as indicated in Figs. 2 and 3, around two arms 23, 23 forming a portion of a bracket 24, which bracket also embodies in its construction the 70 guide-eye 22, said guide-eye passing through the bracket 24 and through the back-plate 10 and being clamped thereto by means of a nut 25 having screw-threaded engagement with the shank of the guide-eye 22. 80

The guide-roll 21 is preferably grooved upon its periphery to receive the line or cord 20 and is rotatably mounted upon a curved rod 26 which is fastened at the opposite ends thereof to the sides 11 and 12 of 85 the casing 6. The rod 26 has its concave side toward the shaft 14 and the guide-roll 21 is slideable longitudinally of said rod 26. The periphery of the roll 21 is adjacent to the concave inner face of the cover 13, so 90 that as said roll moves longitudinally of the rod 26 alternately in opposite directions the line 20 is prevented from coming off of the periphery of said roll. The outer face of the cover 13 is convexly curved and acts as 95 a means for shedding any rain that may fall upon the casing when the same is placed out of doors.

The drum 16 consists of a wooden sleeve 27 which has fastened to its opposite ends, 100 respectively, end plates 28, 28¹ and 29 and 29¹ said end plates 28 and 29 forming bearings for the drum 16 upon the stationary shaft 14.

The drum 15 has a groove 30 in its periphery located between the annular flanges 31 and 32, the cord 18 being coiled up on said drum between the flanges in the groove 30. The flange 32 has gear teeth 33 formed upon its periphery which mesh into a pinion 34. 105 The pinion 34 has fastened thereto a gear 35 and said gears 34 and 35 rotate upon a hub

36 on the casing side 12. The gear 35 meshes into a pinion 37 formed upon the end plate 29 of the drum 16, so that by rotating the drum 15 the gear 33 will rotate 5 the pinion 34 and the gear 35 fast thereto while the gear 35 will rotate the drum 16 by means of the pinion 37 fast to said drum.

The operation of the device hereinbefore 10 specifically described and illustrated in Figs. 1, 2 and 3 is as follows: Assuming the clothes line 20 to be coiled upon the drum 16 and said clothes line extending from the drum 16 around the grooved pulley 21 through the guide-eye 22, by pulling upon 15 the free end of said clothes line the drum 16 will be rotated, thus, through the gearing hereinbefore described, rotating the drum 15, each of the gears and drums being rotated at this time in the opposite direction 20 to the arrows placed upon said gears in Fig. 1, and at this time the weight 19 will move upwardly. When sufficient line has been drawn out and tied to the stationary 25 hooks of the ordinary clothes yard, the clothes line is wound around the arms 23, 23, as seen in Figs. 2 and 3, and the clothes line is then in condition for use. When it 30 is desired to coil the clothes line upon the drum 16 it is detached from the clothes yard hooks and the portion thereof which is wound upon the arms 23, 23 is detached 35 therefrom, and when the clothes line is released the weight 19 will descend, rotating the gears and pinions and drums in the direction of the arrows in Fig. 1 and coiling the clothes line up on the drum 16.

A knot 38 is generally supplied at the end 40 of the clothes line 20 to prevent the end of the clothes line passing through the screw-eye 22.

As the line is coiled upon the drum 16, as hereinbefore described, it will be laid thereon in a series of helices alternately right and left handed, the roller 21 moving alternately 45 from one side of the casing to the other along the rod 26 and being moved by the clothes line 20 so that the same is laid finally upon the drum in a series of helices, and when the line is withdrawn from the drum 50 16, as hereinbefore described, said roll 21 will likewise play longitudinally of the rod 26 in opposite directions alternately.

In Figs. 4 and 5 a modified form of support for the guide pulley is illustrated. Re-

ferring to said figures of the drawing, 9' is 55 the stationary support to which the casing 6' is fastened. 21' is the pulley journaled to rotate in the forked end of the lever 39. The lever 39 is pivoted upon a stud 40 pivoted to an ear 41 upon the backplate 10' 60 of the casing. The stud 40 projects through a slot 42 in the lever 39 and said lever is provided with two arms 43, 43 which extend laterally therefrom in a horizontal direction and are adapted to alternately engage pins 44, 44 fast to the ear 41. Guide rods 45, 45 extend transversely of the casing 6' and are fastened to the side plates of said casing at their opposite ends, respectively, and between these guide rods the lever 39 70 plays as it rocks from side to side in the operation of the device during the coiling or uncoiling of the rope upon the drum 16. The slot 42 in the lever 39 is elliptical in shape with its longer diameter extending 75 longitudinally of the lever and is made somewhat larger than the stud 40 projecting therethrough. In operation, when the lever 39 swings in its arc of movement the axis of such movement changes as necessary. The 80 slot 42, stud 40, arms 43 and pins 44 are so made and positioned that the path of movement of pulley 21' shall approximate the path of movement of pulley 21.

Having thus described my invention, 85 what I claim and desire by Letters Patent to secure is:

A reel having in combination a casing, a drum rotatably mounted in said casing, a cord attached to said drum, a stationary guide for said cord, a guide roll interposed between said guide and drum, over which said cord extends, a stationary curved rod with its concave face toward said drum on which said guide roll is rotatably and slidably mounted, one of the walls of said casing 90 adjacent to said guide roll and rod having an inner face substantially parallel with said rod and constituting a guard whereby 95 said cord is held upon said guide roll. 100

In testimony whereof I have hereunto set my hand in presence of two subscribing witnesses.

EDWARD W. POWERS.
